UNITED STATES PATENT OFFICE.

JOHN GERARD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR CHECK AND CLOSER.

1,177,507.

Specification of Letters Patent. Patented Mar. 28, 1916.

Original application filed November 5, 1915, Serial No. 59,726. Divided and this application filed January 21, 1916. Serial No. 73,335.

To all whom it may concern:

Be it known that I, JOHN GERARD, a citizen of the United States of America, residing at New Britain, Connecticut, have invented a new and useful Door Check and Closer, of which the following is a specification.

My invention relates to improvements in door checks and closers of this application, 10 and this application is a division from my former application Serial No. 59,726, filed November 5th, 1915.

In the drawings: Figure 1 is a perspective view of part of a door casing and door showing my door controller as it would appear in operation, the door being open. Fig. 2 is a relatively enlarged sectional view through part of the door closer mechanism. Fig. 3 is a section on the plane of the line 3—3 20 through both the door and the casing.

For a detailed description of the various parts of the apparatus, not herein fully illustrated or described, reference may be had to my aforesaid application from which this 25 application is a division.

In the present case 53 is a door hinged to a door casing in the usual manner.

59 is a pocket in the door casing on one side to accommodate an arm 56 and part of 30 the arm 55, which arms in this instance constitute one effective means for connecting the door closer to the casing, the said arms being pivotally connected to each other at 57, the arm 56 being pivoted to the door case 35 at 58, and the arm 55 being secured at 16 to the upper end of the door controller spindle. The face of the door 53 has a recess 60 into 40 which the arm 55 projects so that the connection with the upper end of the spindle may be below the upper edge of the door.

52 is a cover plate for the recess 60, said cover plate standing above the spindle. The door controller means includes a checking piston 45 located in a cylindrical bore of 45 the frame 15.

49 is a by-pass leading from the rear of the cylindrical cavity in which the piston 45 is located, forwardly into the main chamber of the frame 15, so that when the piston 50 45 moves from the right to the left as viewed in Fig. 2 the fluid will flow through the by-pass 49 in the direction of the arrow.

48 is the usual check valve in the piston

45 to allow the piston to move freely from right to left.

50 is a by-pass valve which is threaded into the frame 15 and projects into the by-pass 49 so that by screwing the by-pass valve 50 up and down, the cross sectional area of the by-pass may be varied. A suitable packing around the by-pass valve may be provided which may be held in place by a combined packing gland and tubular guide 51, the upper end of which may be slotted as shown to receive a screw driver so as to adjust the gland up and down. This tubular member 51 terminates preferably slightly below the plate 52 and serves as a screw driver guide down to the slotted upper end of the by-pass valve 50. The plate 52 obviously has a small opening directly above the tubular guide 51 to facilitate the introduction of a screw driver. The presence of the tubular guide 51 prevents the valve pin 50 from falling into the interior of the case in 70 the event of the careless removal of the same or in the effort to replace the valve, should occasion require.

In the present case, the invention is chiefly useful in connection with metal doors in 80 which the apparatus is arranged between the two sides of the door as best seen in Fig. 3. Obviously, if the valve pin 50 was of such length as to be easily accessible from the outside, that is to say, if it terminated 85 near the upper edge of the door there would be danger that in adjusting the same, the upper end of the guide pin might be accidentally caused to stand above the upper edge of the door in which event it would be 90 sheared off. By my improvement I am permitted to employ a comparatively short pin located well below the upper edge of the door which pin may be easily inserted or removed and which may be readily adjusted 95 at any time, since by providing the guide 51 the proper tool may be easily inserted and engaged with the by-pass valve.

What I claim is:

1. In a door controller, a frame arranged 100 to be secured in the upper edge of a door and having a checking cylinder and by-pass, a checking piston in the cylinder, a vertically movable by-pass valve having a screw-threaded portion, said frame having a screw-threaded passage for the screw-threaded

portion of said valve, the screw threaded passage in said frame terminating at a point below the upper edge of the frame at a distance greater than the length of the by-pass valve and a tube projecting upwardly around said valve to a point adjacent the upper edge of said frame and serving as a guide substantially as described.

2. In a door controller, a frame arranged to be secured in the upper edge of a door and including a top plate having a hole therein, a cylinder, a checking piston, a by-pass in said cylinder, a by-pass valve arranged beneath the hole in said plate and a guide projecting upwardly from around said valve to a point close to and in line with said hole.

3. In a door controller, a frame arranged to be secured in the upper edge of a door and including a top plate having a hole therein, a cylinder, a checking piston, a by-pass in said cylinder, a by-pass valve arranged to meet the hole in said plate and

a guide projecting upwardly from around said valve to a point close to and in line with said hole, said guide tube surrounding said valve to operate as a packing gland therefor.

4. In a door controller, a frame arranged to be secured between the walls of a door at the upper edge thereof and including a top plate, a controller arm operatively connected with said controller mechanism below said top plate and at one side thereof, a cylinder, a piston, said cylinder having a by-pass, a valve pin for said by-pass provided with a screw-threaded adjusting means, said pin terminating a substantial distance below said top plate, a guide tube surrounding said pin and projecting upwardly to a point adjacent to said top plate and an opening in said top plate in line with said guide tube.

JOHN GERARD.
